UNITED STATES PATENT OFFICE.

HENRY V. WALKER, OF BROOKLYN, NEW YORK, ASSIGNOR TO THE MAAS & WALDSTEIN COMPANY, OF NEWARK, NEW JERSEY, A CORPORATION OF NEW JERSEY.

CHLORHYDRINS AND PROCESS OF MAKING SAME.

972,952.

Specification of Letters Patent. Patented Oct. 18, 1910.

No Drawing.

Application filed January 21, 1909. Serial No. 473,497.

To all whom it may concern:

Be it known that I, HENRY V. WALKER, a citizen of the United States, and resident of Brooklyn, in the county of Kings and State 5 of New York, have invented certain new and useful Improvements in Chlorhydrins and in the Process of Making the Same, of which the following is a specification.

This invention relates to improvements in 10 chlorhydrins and in the process of making the same, and its novelty consists in the several successive steps of the process employed.

In a co-pending application for Letters Patent of the United States, filed January 21, 15 1909, and bearing Serial No. 473,499, I have described a process for the preparation of a novel solvent for pyroxylin and other substances. This solvent consists mainly of olefin oxids produced by subjecting chlorhydrins to the action of caustic alkalies, for instance, caustic lime. The production of a suitable body of chlorhydrins is an incident in that process, but the material from which it is produced constitutes a source of supply 25 heretofore unsuspected, and the process of its manufacture involves steps and reactions heretofore undiscovered, and it is, therefore, made the subject matter of this separate application for Letters Patent.

The source of supply of the material to be treated is any material containing a suitable body of unsaturated hydrocarbons, for instance, the oil produced from Scotch shale oil, or by the destructive distillation of various kinds of brown coal. But the material which I prefer to employ is so-called gas naphtha. This is a by product of the ordinary commercial treatment of petroleum. Thus, in the process of refining crude petroleum, the oil is subjected to distillation, the lighter products, such as naphtha and benzine, coming over first. These are followed by the burning oil fraction. At a certain stage of this period of the distillation, it is found that the product coming over is of much lower boiling point, gravity and flashing point than that preceding it. This peculiarity is attributed to a cracking up of the higher hydrocarbons under the influence 45 of the high temperature prevailing in the distillation. It is usual to run the distillation until the product has again risen in gravity, etc., to that of the initial burning oil fraction. This secondary product which is 50 collected separately is then redistilled,

yielding a distillate called "gas-naphtha" and a residue which is added to the burning oil fraction. This material known in the refineries as gas-naphtha has been so called from the use to which it has heretofore been 60 put, namely, the manufacture of gas for heating purposes and the enrichment of illuminating gas.

Whereas American petroleum consists almost exclusively of saturated hydrocarbons 65 or paraffins, the gas-naphtha contains about 40% of olefins and about 60% only of paraffins. Its boiling point ranges from 35° to 125° centigrade. It is believed that its olefins range from 5 to 8 carbons and that 70 they are primary in structure. For example, the C₅ olefin may be represented by the formula:

75

It might be thought that such a mixture of olefins and paraffins as is contained in this gas-naphtha would react with hypochlorous acid produced in any of the usual ways to form chlorhydrins (although so far as 80 known to me no chlorhydrin or oxid of a primary olefin having five or more carbons has been so produced) but it was found not to be so. There are two described methods of preparing hypochlorous acid. The first 85 of these depends essentially upon the reaction of chlorin with mercuric oxid. This method is too expensive to be thought of on account of the great cost of the mercuric oxid employed. The second of these comprises the treatment of hypochlorites of 90 sodium, or calcium, with a dilute acid. In each case free chlorin was present, the yield of hypochlorous acid was small and its solution was dilute. Both of these methods, 95 therefore, were unavailable. I was, therefore, obliged to find another method of producing the hypochlorous acid.

I discovered that if there was added to a 100 solution of a suitable hypochlorite, for instance, hypochlorite of soda, a sufficient quantity of a suitable bicarbonate, for instance, bicarbonate of soda, to convert both the free alkali and the sodium in combination in the hypochlorite, into sodium carbonate, then a solution was obtained which contained hypochlorous acid, free from chlorin and which reacted readily with the olefins of the gas-naphtha. This process of 105 producing hypochlorous acid free from 110

chlorin I believe to be original with myself and it is made the subject matter of a separate application for Letters Patent of the United States, filed January 21, 1909, and bearing Serial No. 473,498.

In the practice of my process of making chlorhydrins, the gas-naphtha, comprising a mixture of olefins and paraffins as stated or other suitable material containing the olefins, is first placed in a vessel provided with means for agitating and cooling its contents. In another suitable vessel is placed a solution in water of a suitable hypochlorite, for instance, hypochlorite of soda, dissolved in water. It is preferable to use a separate vessel as stated, but not at all essential, since the gas-naphtha, hypochlorite and bicarbonate of soda or the equivalent materials may be all three mixed together and allowed to react in the same vessel. A solution of the hypochlorite containing from 15 to 25 per cent. of NaOCl is of convenient strength. To this is added a sufficient quantity of a soluble bicarbonate of a fixed alkali, preferably bicarbonate of soda, to react therewith to form hypochlorous acid. A proper proportion to employ is about 75 parts of the hypochlorite of soda (NaOCl) to about 85 parts of the bicarbonate of soda (NaHCO₃). The bicarbonate may be added in the form of a saturated aqueous solution, or mixed with an amount of water insufficient for solution or in the dry state. There is no free chlorin produced. The mixture of hypochlorite and bicarbonate of soda, in which the hypochlorous acid is formed is then added to the vessel containing the gas-naphtha, or other material, and the contents are agitated and cooled. The reaction will take place at ordinary temperatures without cooling, but the best results are obtained by preventing the rise of temperature due to the reaction and maintaining the temperature at or below 15° centigrade. This reaction should continue for about four hours. At the end of that time the oily portion of the liquid containing the chlorhydrins is allowed to separate from the aqueous portion of the liquid, the latter being drawn off and rejected. The oily portion is then washed with a small amount of water to remove any hypochlorite which might remain and it is dehydrated. If it is desired to accomplish such dehydration quickly, calcium chlorid may be employed. If time is not essential, the water may be allowed to separate out by gravity. The discovery upon which this part of the process depends is that the chlorhydrins remain in the oily part of the liquid and not in its aqueous part. The paraffins, or residual hydrocarbons, which are mixed with the chlorhydrins are then removed. This is accomplished by distillation at a suitable temperature below the boiling point of the chlorhydrins, which is about

170° centigrade. Such a temperature is about 140° centigrade. Of course, the temperature during this step of the process must be lower than that at which the chlorhydrins will be carried over. After such 70 distillation, the residual liquid consists of the chlorhydrins sought to be obtained.

The reactions apparently involved may be illustrated in connection with the C₆ olefin:—

In carrying out the above process, it is advisable first to ascertain the percentage of olefins in the material employed by determining the amount of bromin absorbed, using the well known methods for this purpose. From this, the quantity of hypochlorous acid necessary to be used is shown by the above equation No. 2, a slight excess of such acid being used to insure as complete a conversion of the olefins as possible.

The mixture of chlorhydrins above described is a yellowish liquid having a characteristic camphor-like odor, insoluble in water, miscible with such organic solvents as alcohol, ether or benzin, having a specific gravity ranging from about 1.015 to about 1.045 at 15° C., tending to darken when distilled, (apparently on account of the decomposition of the higher chlorhydrins in the mixture) and having the characteristic chemical property of being decomposed by caustic alkali with the removal of hydrochloric acid, and the formation of olefin oxids. These olefin oxids, and consequently the chlorhydrins from which they are derived by decomposition with caustic alkali as just stated, are of primary structure. This is demonstrated by the following considerations:

1. The origin of the gas-naphtha product from which my chlorhydrins are derived shows that the latter are of primary structure because it is well known that the paraffins of petroleum are of primary structure and it has been shown by actual chemical investigation (see Armstrong and Miller *Chem Soc. Transactions* 1886, I, 79-93; *Ber. (Ref.) XIX*, 244) that the action of heat upon said paraffins produces primary olefins. It follows, therefore, that the gas-naphtha olefins used as an initial material of the products of my present invention are likewise of primary structure, and therefore the chlorhydrins derived therefrom must also be primary.

2. It is a known characteristic property of primary olefin oxids (see Eltekow *Ber. XVI*, 396) that they do not combine with water, whereas the secondary and tertiary oxids do combine with water to form gly-

cols. Since the olefin oxids derived from the chlorhydrins of my present invention do not combine with water, it follows that they must be of primary structure.

5 1. I claim—

10 1. The process of making chlorhydrins which consists in mixing a bicarbonate of a fixed alkali and a solution containing a hypochlorite of a fixed alkali and reacting therewith upon an olefin.

15 2. The process of making chlorhydrins which consists in first mixing a bicarbonate of a fixed alkali and a solution containing a hypochlorite of a fixed alkali, second agitating an olefin therewith, and at the same time preventing any rise of temperature due to the reaction.

20 3. The process of making chlorhydrins which consists first in subjecting a solution of a hypochlorite containing an excess of free alkali to the action of a bicarbonate of a fixed alkali in excess, whereby there results an alkaline solution of hypochlorous acid free from chlorin, and reacting there-

25 with upon an olefin.

4. The process of making olefin chlorhydrins having five carbons and over, consisting in mixing a bicarbonate of a fixed alkali and a solution containing a hypochlorite of a fixed alkali, reacting therewith upon gas naphtha, separating the oily layer containing the chlorhydrins from the aqueous layer, and fractionating the oily layer to obtain the chlorhydrins therefrom.

35 5. The process of making olefin chlorhydrins having five carbons and over consisting in first mixing a bicarbonate of a fixed alkali and a solution containing a hypo-

chlorite of a fixed alkali, second, agitating gas naphtha therewith, and at the same time 40 preventing any rise of temperature due to the reaction, and third, separating the oily layer containing the chlorhydrins from the aqueous layer, and fourth, fractionating the liquid so separated to obtain the chlorhydrins therefrom.

6. As new products of manufacture, the chlorhydrins of the primary olefins having five or more carbons, being yellowish liquids having characteristic camphor-like odor, 50 insoluble in water, miscible with such organic solvents as alcohol, ether or benzin, and having the characteristic chemical property of being decomposed by caustic alkali with removal of hydrochloric acid and formation 55 of olefin oxids which do not combine with water.

7. As a new product of manufacture, a mixture of primary olefin chlorhydrins, being a yellowish liquid having characteristic 60 camphor-like odor, being insoluble in water, miscible with such organic solvents as alcohol, ether, or benzin, having specific gravity ranging from about 1.015 to a specific gravity of about 1.045 at 15° C., tending to 65 darken on distillation and having the characteristic chemical property of being decomposed by caustic alkali with removal of hydrochloric acid and the formation of olefin oxids which do not combine with water.

Witness my hand this 19th day of January 1909, at New York, N. Y.
